UNITED STATES PATENT OFFICE.

FERDINAND J. TILLMAN, OF ST. LOUIS, MISSOURI, ASSIGNOR TO YARD-O-METER CORPORATION, OF ST. LOUIS, MISSOURI.

CALCULATING MACHINE.

Application filed February 12, 1920. Serial No. 358,164.

To all whom it may concern:

Be it known that I, FERDINAND J. TILLMAN, a citizen of the United States, residing at St. Louis, Missouri, have invented 5 certain new and useful Improvements in Calculating Machines, of which the following is a full, clear, and exact description.

This invention relates to calculating or computing of the yardage and prices there- 10 of of fabric materials as they are passed through a measuring machine. The principle contained in this invention being disclosed in my pending application filed June 16, 1919, Serial No. 304,681, for U. S. Letters Patent thereon pertaining to a combined computing and measuring machine.

The primary object of this invention is to provide an improved arrangement and combination of a plurality of calculating scales. 20 Another object of this invention is in providing an improved movable calculating sheet bearing a plurality of price indicating characters and an improved arrangement of indicating lines which is cooperable with 25 the characters of the sheet the length and width thereof.

A further object of this invention is in combining a grade scale and a quantity scale with the movable indicating scale or sheet, 30 in which the indicating sheet is made simultaneously cooperable with both the grade and quantity scales.

Other and further objects will appear in the specification, reference being had there- 35 to in view of the accompanying drawings, and in which—

Figure 1 is a plan view of this improved computing machine.

Fig. 2 is a fragmentary side view of a 40 portion of Figure 1, taken in the direction of the arrow 2 of said Figure 1;

Fig. 3 is a transverse section taken on the line 3—3 of Figure 1;

Fig. 4 is a transverse section taken on the 45 line 4—4 of Figure 1;

Fig. 5 is an enlarged view of the calculating indicating price sheet used in connection with the computing mechanism and forming one of the essential elements thereof;

Fig. 6 is an enlarged view of the yardage 50 indicating carriage;

Fig. 7 is an enlarged, vertical, transverse section taken on the line 7—7 of Fig. 6;

Fig. 8 is a diagrammatic view of the cal-

culating indicating sheet, greatly reduced in size.

Referring to the drawings: 1 designates a base member having side members 2 and 3 and end members 4 and 5, the side member 3 at its upper end terminating into a horizontal portion 6, and paralleling said portion 6 and engaged between the end members 4 and 5 is a portion 7 bearing a yard scale 8, said portion 7 being spaced apart from the portion 6 and forming a sight opening 9 therebetween.

The arrangement of the side members 2 and 3 and end members 4 and 5 forms the housing 10, and located in said housing above the base portion 1 are a pair of horizontally and parallelly arranged roller shafts 11 and 12, each bearing a rigidly secured roller 13 and 14, respectively. Secured at its ends to each of said rollers 13 and 14 is a traveling or movable sheet 15, bearing a plurality of calculating characters, which will hereinafter be more fully described.

The ends of the roller shafts 11 and 12 are supported in the respective end members 4 and 5, and also supported by said end members is a horizontal shaft 16, which is arranged above said shafts 11 and 12, and secured rigidly to said shaft 16 is a roller 17, over which the sheet 15 passes, as shown more clearly in Fig. 4. The shaft 16 of the roller 17 extends through the end member 5, and rigidly secured to said shaft outside of said member 5 is a spur gear 18, said gear meshing with pinions 19, one of which is securely mounted to each of the roller shafts 11 and 12 of the respective rollers 13 and 14, and secured to the shaft 12 adjacent its pinion 19, is an operating handle 20.

As afore related in the objects of this invention, the theme thereof is to provide an improved calculating attachment or mechanism pertaining to measuring machines and the like, and in order to bring out more clearly the advantages of this improved device, the principles thereof are contained in having a combination of scales that are readable relative to one another, and in which a scale 21 is provided on the horizontally extending portion 6, and in the showing of Fig. 1, a plurality of prices represent said scale and is termed a grade scale as pertaining to different grades of goods to be sold,

and incidentally the price thereof calculated. The second scale in the combination is the yardage scale 8, which is located oppositely from the grade scale 21, across from the sight opening 9, said scale 8 being termed the quantity scale.

The third scale in the combination of scales is comprised in the movable sheet 15, which bears a plurality of calculating characters that are in line with the quantity scale as said sheet is passed thereby or thereunder, said characters also being arranged in column formation transversely of the sheet 15, so that the columns will align with the sight opening 9, which is located between the scales 8 and 21. With reference to Fig. 1, it is to be noted that there are two columns of figures 22 and 23 on sight in the opening 9, each item or figure of the column 22 being in line with the one quarter yard measurements of the scale 8, whereas each figure in the column 23 is in line with each one-eighth yard measurement of said scale 8. Regarding the just mentioned description of the two column formation of the sheet 15, and with reference to Figure 5 of the drawings, said sheet is approximately filled from end to end with like sets of such columns that are located adjacent each other, as shown in said figure, said columns extending transversely of the length of said sheet, and as shown are arranged in two-column formation as denoting headings or values, such as 15, 20, 25 and so on, up to 33, 3.20, and 4.00 as denoting dollars and cents, and as mentioned, the figures in the 23 column, as relating to one-eighths of yards, will also mean the prices of the eighths of yards, whereas the figures in each column 22, 40 indicate quarters of yards and their prices. For instance, with respect to Figure 1, it is to be noted that the double column, under the heading 1.00, as relating to \$1.00 per yard, will give any price desired relative to any part of the ten yards called for or fractions thereof, on the quantity scale 8, as said scale is readable in eighths of yards, quarters of yards and one yard. For instance, the one yard on the scale 8 indicates \$1.00, whereas one and one-eighth yard will indicate \$1.13, whereas the yard and a quarter indication of said scale denotes \$1.25.

In addition to the aforesaid relative to the sheet 15, as shown in Figures 1 and 5, said sheet is provided with a diagonal line that extends lengthwise thereof from the approximately lowest to the highest figure of said sheet, said line being preferably differently colored from the type or figures of said sheet, and is adapted to represent an indicating line 24. In carrying on the operation of this improved device the ends 25 and 26 of the sheet 15 are respectively secured in any desired manner to the respective rollers 13 and 14, said sheet being long enough, com-

mensurate with the number of characters or prices to be placed thereon, and in which the sheet is adapted to be wound from one of said rollers to the other.

In the event that a customer desired to buy so many yards of a certain grade of goods, the grade of goods to be sold is first determined, and for the purpose of illustration it is assumed that the \$1.00 grade of goods is elected, meaning goods at \$1.00 per yard, and the customer desires to purchase six yards of the one dollar grade, the handle 20 is turned until the indicating line 24 of the sheet 15 is directed to the grade indication of \$1.00 and in which the moving of the sheet 15 to a position of alinement with the \$1.00 grade, also carried up the two or double columns 22 and 23, as relating to the \$1.00 heading of said sheet, so that both of said columns are in a position for inspection through the sight opening 9 (see Fig. 1,) in which the \$6.00 calculation, as denoting six yards at \$1.00 per yard, is found to be opposite the six yard mark or graduation of the quantity scale 8. After the finding of the price of the six yards of goods, if the customer desires or decides to change the original amount of six yards to a greater or lesser amount of yards of the one dollar grade, any desired amount of yards and price thereof, up to ten yards of goods, can be readily ascertained by comparing the yardage indication of the scale 8 with the calculations of the \$1.00 double column of the sheet 15.

If the next order of goods desired to be calculated is of a grade costing 15¢ per yard, the handle 20 is again manipulated, thereby causing the sheet 15 to be moved until the indicating line 24 thereof is brought to a position of indication with the price 15 of the grade scale 21, in which the double column headed by the numeral 15, as denoting 15¢ per yard will be brought to an inspecting position within the sight opening 9, in which the fractions of yards at said rate of 15¢ per yard can readily be ascertained by comparing the graduations of the quantity scale 8 with the fractional prices under the 15¢ per yard double column.

Referring again to the aforementioned illustration regarding the price of six yards of goods at \$1.00 per yard, it was desired that six yards of goods be measured and cut, the front edge of the material is introduced between the upper friction roller 27 and lower squeezing roller 28, and the material is pulled therethrough, and the carriage 29, bearing the indicating line 30, (which is mounted on the spiral shaft 31 and normally in position against the end member 5,) will be moved by the actuation of said shaft 31 to the desired position of indication relative to the six yard graduation of the quantity scale 8, where pulling force on the goods is

discontinued and the measured goods is cut by the actuation of the knife 32. Since the quantity scale 8 and sheet 15 are adapted to calculate in one-eighths portions, it is essential that a locking device be provided where accuracy in one-eighths portions be provided relative to the feeding and measuring of the goods being pulled through the friction roller 27 and the squeezing roller 28. In this connection a locking lever 33, which is fulcrumed at 34 to the end member 4, is provided, said lever at one end bearing an engaging portion 35, which is adapted to engage into a single recess 36, provided in the friction roller 27 (see Fig. 3), said recess 36 being disposed diametrically from the marking arrow 37 formed in the periphery of said roller 27 and being part of the peripheral scale 38 of said roller, said scale having a circumferential length of four and one-half inches as denoting one-eighth of a yard. This locking lever is for the purpose of preventing the goods being cut, unless the proper amount of material has been fed through the rollers 27 and 28, in which the material cannot be cut until the total length thereof measures in portions of one-eighths, as said lever 33 when lowered will bear against the back or upper edge of the knife 32, thereby swinging said knife downwardly and severing the goods at the cutting edge 39 of the table 40. In this connection, if the recess 36 of the roller 27 is not in alinement with the engaging portion 35 of the lever 33, then said lever cannot be moved downwardly against the knife 32. If, however, the operator desires to sever the goods in positions

other than the one-eighths measurements, the knife 32 can be operated without the aid of the lever 33.

For adjusting the squeezing roller 28 relative to the friction roller 27, the pivoted arm 41 of said roller 28 is provided with a pin 42 which is engaged in a cam way 43 of an adjusting lever 44, said lever bearing a detent 45, which is relatable with the ratchet bar 46. The carriage 29 is provided with swingingly mounted spring actuated tooth engaging member 47, which is adapted to release said carriage 29 from the spiral shaft 30 relating to shifting said carriage to its normal position on said shaft.

What I claim is:

A calculating machine, comprising a casing having a longitudinal slot through one side thereof, a column of multiplicand numbers on the casing adjacent to one side of the slot, a column of multiplier numbers on the casing adjacent to the opposite side of the slot, a sheet operatively supported in the casing, a series of columns of products on the sheet, means for operating the sheet transversely of and adjacent to the slot to different positions to selectively display the columns of products through said slot, and a diagonal line on said sheet arranged to indicate the respective multiplicand numbers in calculation in which the column of products visible through said slot are the products of the multiplicand number so indicated by said line multiplied by the various multiplier numbers in said column of multiplier numbers.

FERDINAND J. TILLMAN.
